UNITED STATES PATENT OFFICE.

LINCOLN MOSS, OF NEW YORK, N. Y., ASSIGNOR TO THE ROBINS CONVEYING BELT COMPANY, OF NEW YORK, N. Y., A CORPORATION OF NEW JERSEY.

CONVEYER.

No. 828,331

Specification of Letters Patent.

Patented Aug. 14, 1906.

Application filed July 29, 1903. Serial No. 167,377.

To all whom it may concern:

Be it known that I, LINCOLN Moss, a citizen of the United States, and a resident of the borough of Manhattan, city, county, and State of New York, have invented certain new and useful Improvements in Conveyers, of which the following is a specification accompanied by drawings.

This invention relates to conveying apparatus, but more particularly to that class of apparatus known as "bridge conveyers;" and the objects of the invention are to improve upon the construction of such apparatus and increase its efficiency of operation.

Another object of the invention is to enable material to be delivered to a storage pile without necessitating a drop from a great height, which is apt to break the material to be stored. According to this invention breakage is reduced to a minimum.

Further objects of this invention will hereinafter appear; and to these ends the invention consists of apparatus for carrying out the above objects, embodying the features of construction, combinations of elements, and arrangement of parts having the general mode of operation substantially as hereinafter fully described and claimed in this specification and shown in the accompanying drawings, in which—

Figure 1 is a side elevation of apparatus embodying the invention. Fig. 2 is a plan view of the same, partly broken away. Fig. 3 is an end elevation of the apparatus. Fig. 4 is an enlarged detail view, partly in section, showing the universal joint for the movable arm; and Fig. 5 is an enlarged detail view of a side elevation of the universal joint.

Referring to the drawings, A represents a railroad-track or other suitable way upon which loaded cars are adapted to travel, and B represents a storage pile to which the loads on the cars are adapted to be delivered. The pile B may represent coal or any other suitable material. The supporting structure C for the railroad-tracks A is provided with chutes D for the discharge of material from the cars.

E represents a traveling bridge, provided with the rollers F running upon the tracks G, which tracks are arranged, as shown, at each side of the storage pile B, so that the bridge extends across the pile. The bridge E may be of any suitable and desirable construction

in order to afford a supporting-framework for the apparatus to be described.

At one side of the bridge is a tower H, to which is universally pivoted a frame I, provided with the continuously-traveling belt conveyer J, passing over the pulleys K and L at the respective ends of the frame I. In this instance the frame I is pivoted for vertical movement about the shaft 25, which is shown as the axis of the pulley K, although the pivotal axis of the frame and the axis of the pulley need not be the same, and other suitable constructions may be provided, if desired. The shaft 25 has its bearings in the bracket 26, which in turn is mounted to rotate horizontally on the vertical pivot-pin 27, secured upon the frame of the tower. The construction described thus forms a universal joint for the frame I.

Suitable means are provided for raising and lowering the outer end of the frame I and conveyer J, as by means of the block P and tackle Q. The tackle for raising and lowering the conveyer J is preferably rove through blocks on the bridge and on the tower and taken to a drum on the hoisting-engine R. In other words, the conveyer J is pivoted on the tower at its receiving end or tail end in such manner as to be capable of angular movement in all directions, this movement being controlled by means situated between the discharge or head end of the conveyer and the bridge.

A continuously-traveling belt conveyer S extends along the tracks A and is supported upon a framework T, connected to the tower of the bridge, so that the entire conveyer S moves with the bridge. Another conveyer U, as shown, is carried by the bridge and extends from the conveyer S in an upward direction, discharging upon the tail end of the conveyer J, so that material received upon the conveyer S is carried upwardly to conveyer J and from thence discharged upon the storage pile. As shown, suitable tracks V extend at each side of the conveyer S, and a traveling hopper W runs upon said tracks. Material is delivered from the chute or chutes D into the traveling hopper W and from thence upon the conveyer S.

The cars upon the trestle C are unloaded, therefore, upon the conveyer S, and the coal or other material is carried by the said con-

veyer to its head end and there discharged upon the tail end of conveyer U through the chute X. Conveyer U in turn discharges the coal through a chute Y upon the tail end 5 of the conveyer J, from the head end of which it is discharged upon the storage pile B.

When starting the pile, the head of conveyer J is lowered as near the ground as possible without giving the conveyer so great an incline that the coal will slide on the belt, and then the conveyer is gradually raised as the pile grows in height, being kept a short distance above the apex of the pile. In this way the coal has only a slight drop from the conveyer 15 to the storage pile and breakage is reduced to a minimum. In handling anthracite coal especially this is a very important consideration, as it is also in case of numerous other materials. It is often found necessary to store 20 various materials to a height of seventy-five feet or more, and when a car or elevator or a fixed conveyer is used for the purpose material has to be dropped from the height of the bridge, and the resultant breakage is excessive. 25

In order to suitably handle the coal on the storage pile B, buckets Z are shown, which buckets are connected by operating-ropes with the engine R on the tower. According 30 to this invention it will be seen that a suitable support is provided for the conveyers, and in this instance said support being shown in the form of a traveling bridge or a traveling framework; but the invention is not to be understood as being limited to a bridge 35 which travels. Upon this bridge are disposed two conveyers at an angle to each other, arranged in different planes, and another conveyer connects the discharge end 40 of one with the tail end of the other. The conveyer S, extending in the direction of movement of the bridge, may be termed the "receiving-conveyer," since it receives the material from the cars to be unloaded. The 45 conveyer J, the discharge end of which is movable in all directions, may be termed the "discharging-conveyer," since the material is delivered from the discharge end upon the storage pile. The conveyer U, arranged between the conveyers S and J, may be termed 50 the "connecting-conveyer," since it connects the discharge end of one conveyer with the tail end of the other.

Obviously some features of this invention 55 may be used without others, and the invention may be embodied in widely-varying forms. Therefore, without limiting the invention to the construction shown and described, nor enumerating equivalents, I 60 claim, and desire to obtain by Letters Patent, the following:

1. A conveying apparatus comprising a traveling support constructed to extend over a stock pile, a conveyer arranged to discharge on said stock pile and capable of an-

gular movement, said conveyer being supported by said support at one side of the stock pile and constructed to extend inwardly over the stock pile, and means for controlling the angular movement of said conveyer, for substantially the purposes set forth. 70

2. A conveying apparatus comprising a traveling bridge arranged to span a stock pile, a conveyer arranged to discharge on said pile and having the receiving end thereof supported at one side of the bridge, the discharge end being capable of movement in any direction, and means for controlling the angular movement of said conveyer, for substantially the purposes set forth. 75

3. In conveying apparatus, the combination with a traveling support, an upper and a lower conveyer carried thereby and movable therewith, the upper conveyer being capable of angular movement and having its receiving end at a higher elevation than the lower conveyer, of means for transferring material from the lower to the upper conveyer, for substantially the purposes set forth. 80

4. In conveying apparatus, the combination of a traveling support, two conveyers carried thereby and movable therewith, one conveyer being capable of angular movement and arranged at a higher elevation than the other conveyer, and means separate from both of said conveyers for transferring material from the other conveyer to the conveyer capable of angular movement, for substantially the purposes set forth. 85

5. In conveying apparatus, the combination of a traveling support and two conveyers carried by the support and disposed at an angle to each other and in different planes, the upper conveyer being capable of angular adjustment, and another conveyer connecting the discharge end of the lower conveyer with the receiving end of the upper conveyer, for substantially the purposes set forth. 90

6. In conveying apparatus, the combination of two conveyers arranged at an angle to each other and in different planes, and a traveling support for the same, the discharge end of one of said conveyers being movable in a vertical plane, means for controlling said movement, and a third conveyer connecting the two said conveyers, for substantially the purposes set forth. 95

7. In conveying apparatus, the combination of a traveling bridge, a receiving-conveyer extending in the direction of the movement of said bridge, a discharging-conveyer disposed at an angle to said receiving-conveyer and capable of movement in a vertical plane, and a connecting-conveyer interposed between the receiving and discharging conveyers and arranged at an angle to each, for substantially the purposes set forth. 100

8. In conveying apparatus, the combination of a traveling bridge and receiving-dis-

charging, and connecting conveyers arranged thereon, the discharging conveyer being capable of movement in a vertical plane, for substantially the purposes set forth.

- 5 9. In conveying apparatus, the combination with a traveling support, two conveyers carried thereby and movable therewith, one conveyer being supported at a higher level than the other and being angularly adjustable, and means for lifting material discharged by the lower conveyer and depositing the said material upon the upper conveyer, for substantially the purposes set forth.
- 15 10. In conveying apparatus, the combination

of a traveling bridge, a conveyer extending in the direction of movement of the bridge, a conveyer angularly adjustable in a vertical plane disposed at an angle to the first-mentioned conveyer, and a third conveyer interposed between the other two conveyers and arranged at an angle to each, for substantially the purposes set forth. 20

In testimony whereof I have signed this specification in the presence of two subscribing witnesses. 25
